The ornamental design for a cord adjuster for tent, as shown and described.

DESCRIPTION

FIG. 1 is a front, top, and left side perspective view of a cord adjuster for tent, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, bottom, and right side perspective view thereof;

FIG. 9 is a cross-sectional view taken along line 9-9 shown in FIG. 4; and,

FIG. 10 is a reference view showing the cord adjuster for tent in use.

The long dash short dash broken lines and arrows shown in FIG. 4 are used to identify the cross-sectional view and form no part of the claimed design. The evenly spaced broken lines shown in FIG. 10 depict environment and form no part of the claimed design.
